UNITED STATES PATENT OFFICE.

WALTER P. MURPHY, OF NEW YORK, N. Y.

CAR ROOF.

Application filed September 1, 1920. Serial No. 407,288.

To all whom it may concern:

Be it known that I, WALTER P. MURPHY, a citizen of the United States, residing in New York, in the county of New York and State of New York, have invented a new and useful Improvement in Car Roofs, of which the following is a specification.

This invention relates to improvements in car roofs and more particularly to outside metal roofs comprising a plurality of metal sheets, movably mounted on the substructure.

It is the object of this invention to enable such roofs to accommodate the various distortions arising from the racking and weaving of the car and to provide flashings particularly for the ends of the car, which will be capable of relative movement when the car goes out of square.

The invention consists in the parts and combination of parts, hereinafter described and shown upon the accompanying drawing, in which:

Figure 1 is a plan view of the end portion of a car roof embodying this invention with parts broken away.

Figure 2 is an enlarged detail view in perspective of a side section of the improved end flashing.

Figure 3 is an enlarged detail view in perspective of the central section of the end flashing.

Figure 4 is an enlarged detail view in perspective of a side section of an end cap.

Figure 5 is an enlarged detail view in section taken on the line 5—5 of Figure 1.

In the construction illustrated, the roof sheets 1 extending transversely of the car from ridge to eaves, are rebent upon themselves on the under side at the eaves to engage or hook into a side flashing 2 rebent upon its upper side, with the end sheets narrower at the eaves than at the ridge allowing flexibility of the roof to accommodate distortions.

The end flashing as constructed in accordance with this invention comprises three sections. The side sections 3 extending from adjacent the ridge beyond the side flashing 2 lie over and upon the sheathing boards 4 and side flashing, and are wider at the eaves than at the ridge with inner edges substantially parallel to the edge of the end sheet, under which they extend. Each of these side sections is provided with a flange 5 depending over the

end of the car with the eaves end 6 of the section adjacent the side flashing rebent on the under side to engage or hook into the side flashing. These sections are each provided with a struck up rib 7 extending substantially throughout and adjacent the inner edge. The end center flashing comprises a plate 8 lying over and upon the adjacent ends of the side flashing sections 3 at the ridge, extending to the struck up ribs 7 and is provided with a depending flange 9 lying over and upon the flanges 5 of the side sections 3 on the end of the car. The side sections 3 are nailed to the sheathing boards between the inner edge and the rib 7 with the flange 5 of the section and the flange 9 of the end center flashing nailed to the end of the car or end plate 10.

End caps are placed over the edges of the end sheets and are also preferably constructed in three sections. The side sections 11 of the end caps extend from adjacent the ridge over the side of the car and lie over and upon the end roof sheets extending inwardly with the inner edge parallel to and terminating short of the inner edge of the end flashing 3. Each end cap section is provided with a flange 12 depending over the end of car below the flanges 5 and 9 of the end flashing, and which is nailed to the end of car or end plate 10, the eaves end of the end sections being provided with a flange 13 depending over and engaging the side plate of the car. A center end cap 14 covers the space between the adjacent ends of the cap sections 11 at the ridge.

As shown in the enlarged sectional view of Figure 5 and by the broken away parts of Figure 1, the struck up ribs 7 of the end flashing 3 are substantially parallel to the end edge of the adjacent roof sheet 1 and supports it above the body of the end flashing. The end caps 11 extend beyond the ribs 7 and the inner edges 15 are preferably rebent on the under side to lie upon the upper portion of the end sheet and hold it loosely against the ribs 7 of the end flashing which allows movement of the end sheets and at the same time causes any water that may be blown under the cap to be drained off into the eaves flashing.

The struck up rib 7 not only adds to the rigidity of the inner edge of the end flashing but allows the end roof sheet to re-enter freely should the sheet be pulled out over

the rib by extreme weaving. In such an event the single thickness of the end flashing resting upon the wood sheathing will allow the edge of the end sheet to ride thereover and re-enter between the flashing and cap without jamming, buckling or otherwise disfiguring the sheet.

What I claim is:

1. An end flashing for a car roof comprising sections having portions resting on the end portion of the car and flanges overhanging the end of the car, the portion of the flashing resting on the car being provided with a struck up rib extending substantially throughout its length.
2. An end flashing for a car roof comprising sections having portions resting on the end portion of the car and flanges overhanging the end of the car, the portion of the flashing resting on the car being provided with a struck up rib substantially parallel to and adjacent the inner edge extending substantially throughout its length.
3. An end flashing for a car roof comprising side sections each resting on the end portion of the car and having flanges overhanging the end of the car, the portion of the flashing resting on the car being provided with a struck up rib extending substantially throughout its length, and a center section overlying the adjacent ends of the side sections.
4. An end flashing for a car roof comprising side sections each resting on the end portion of the car and having flanges overhanging the end of the car, the portion of the flashing resting on the car being provided with a struck up rib adjacent the inner edge extending substantially throughout its length, and a center section overlying the adjacent ends of the side sections.
5. A metal car roof comprising roof sheets arranged transversely of the car and having rebent eaves portions, side flashings having rebent portions co-operating with the eaves portions of the roof sheet, and an end flashing for the car having a struck up rib along its length under the roof sheets, the eaves ends of said flashing being rebent so as to co-operate with the rebent portions of the side flashings.
6. A metal car roof comprising roof sheets arranged transversely and having rebent eaves portions, side flashings having rebent portions co-operating with the rebent eaves portions of the roof sheets, and an end flashing for said car, said end flashing comprising side sections each having a struck up rib along its length and a center section overlying the adjacent ends of the side sections between the struck up rib and the end of the car.
7. A metal car roof comprising roof sheets arranged transversely of the car and having rebent eaves portions, side flashings having rebent portions co-operating with the rebent eaves portions of the roof sheet, and an end flashing for said car, said end flashing comprising side sections tapering in width from eaves to ridge, each having a struck up rib along its length, arranged substantially parallel to and adjacent the inner edge.
8. A metal car roof comprising an end roof sheet tapering from ridge to eaves, an end flashing tapering from eaves to ridge, arranged beneath said sheet having a struck up rib along its length, an end cap for said end sheet and end flashing and means for securing said end flashing and cap to the car.
9. A metal car roof comprising end roof sheets, an end flashing arranged beneath said sheets, said end flashing being made in sections, each side section having a struck up rib along its length and a central section overlying the adjacent ends of the side sections, said end sheets tapering from ridge to eaves and said flashing side sections tapering from eaves to ridge, end caps for said end sheets and said end flashing having a portion extending beyond the ribs of said flashing side sections and substantially parallel therewith, and means for securing the end sheet flashing and end sheet caps to the car.

WALTER P. MURPHY.
